UNITED STATES PATENT OFFICE.

RODERICK W. HADDOCK, OF INDEPENDENCE, OREGON.

ORE-SEPARATING DEVICE.

1,269,704.

Specification of Letters Patent. Patented June 18, 1918.

Application filed October 5, 1916. Serial No. 123,976.

To all whom it may concern:

Be it known that I, RODERICK W. HADDOCK, a citizen of the United States, residing at Independence, in the county of Polk and State of Oregon, have invented certain new and useful Improvements in Ore-Separating Devices, of which the following is a specification.

This invention relates to ore separating devices, and more particularly, to an apparatus operating by the improved dry process for separating minerals from their ores.

The invention has more especial reference to a construction of the character mentioned, whereby, gold, silver and other valuable minerals, may be separated from their ore by means of compressed air, which is delivered onto the ore as the same is fed into the separator, the device being particularly adaptable for use in dry climates.

More particularly, the present invention has reference to the novel construction and arrangement of the separator, the same comprising a tubular conveying tube, having a portion thereof formed in a zig-zag manner whereby, to cause the minerals to be deflect- ed into suitable pockets carried by the conveyer for this purpose.

Another important characteristic of the invention, resides in the provision of an auxiliary pneumatic tube, which communicates with the mineral receiving receptacle, for maintaining the same clear of waste.

The invention also embraces a novel form of hopper, whereby the ore may be fed into the tubular conveyer, the same hopper being provided with a cutoff for controlling the passage of the ore into the conveyer and a screening member whereby the ore is fed into the tube in extremely fine particles, an inclined baffle plate carried by the hopper and extending for a slight distance into the conveyer tube, thereby providing for means whereby the compressed air contained within the tube will be prevented from blowing ore upwardly as the same is delivered thereinto.

Among the aims and objects of the invention may be recited, the provision of a separator of the character mentioned, with a view to compactness, and in which the parts are few, the construction simple, the cost of production small, and efficiency and operation high.

Other and further improvements and novel details in the construction and ar-

angement of parts will be appreciated from the description to follow, which for a clear understanding of the invention, should be considered in connection with the accompanying drawings, forming a part hereof and wherein the preferred embodiment of the invention is shown for the purpose of illustration.

In the drawings:

Figure 1 is a top plan of my improved separator.

Fig. 2 is a side elevation thereof,

Fig. 3 a detail in section of one of the mineral receiving receptacles or pockets, and

Fig. 4 is a vertical section in detail through the hopper.

Referring now more particularly to the drawings, wherein like reference numerals designate corresponding parts throughout the several views, I provide a tubular conveyer indicating the same in its entirety by the numeral 1, which conveyer is composed of a plurality of sections of piping, generally indicated by the numeral 2, the said sections being joined by means of suitable unions 3 while the pneumatic blower 1' is connected to the tubular conveyer for forcing air therethrough. As will be obvious, a portion of the tubular conveyer 1 is a substantially straight line, as at 4, while the remaining portion thereof is so arranged as to provide a plurality of coiled or zig-zag sections generally indicated as 5, the said sections being connected with each other and with the portion 4 of the tubing by means of elbows 6, the ends of which may be provided with threads which threads are engageable with complementary portions arranged upon the opposite extremities of said portions 5. The sections 5 may be and preferably are, constructed from a plurality of separate pieces of piping, the adjacent ends of which are connected by unions 7 similar to those as designated by the numeral 3.

An opening 8 is arranged within the straightaway portion 4 of the conveyer 1 and has arranged thereover a hopper 9, the upper portion of which is flared outwardly in the usual manner, as at 10 and carries thereupon by means of a flange 11 a wire mesh fabric 12, this fabric serving as means for thoroughly sifting and pulverizing the ore as it is fed into the conveyer 1. An inclined baffle plate 13 is affixed to one side of the hopper 9 and extends for a slight dis-

tance downwardly into the straightaway portion 4 of the conveyer 1, thus, providing for means whereby the compressed air as contained within the conveyer will be prevented from blowing particles of the ore upwardly and out of the hopper, thus, eliminating possible waste. A closure plate 14 having a handle portion 15, is slidably arranged within the hopper 9 preferably adjacent the base portion of the flaring part 10 and is supported upon the wire mesh fabric 11. By this means, it is apparent, that when so desired, the operator may readily move the same forwardly, thereby closing the discharge opening of the hopper and preventing the passage of the ore into the conveyer, if so desired. It is of course, understood, that the hopper 9 is provided with a suitable opening, whereby the closure plate 14 may be received into the hopper.

In order to provide for means whereby the mineral may be separated from the ore as the same passes through the straightaway and zigzag portions of the conveyer 1, I arrange upon the bottom thereof, a series of depending tubular portions 16, the lower extremities of which are externally threaded as at 17 and adapted to have turn in engagement therewith, complementally threaded cap members 18, thus, forming efficient receptacles or pockets. Inclined baffle plates 19 are formed upon one side of the tubular members 16 for a purpose as will be subsequently obvious. A shunt pipe 20, is engaged with the various tubular members 16 and communicates therewith, the remaining end of the same being inserted within the straightaway portion 4 of the conveyer 1, at a point beyond the hopper 9, as shown at 21. Thus, it will be apparent, that when compressed air is introduced into the inlet portion of the conveyer 1, a portion thereof will be shunted into the pipe 20 and delivered into the mineral receiving pockets, thus maintaining the same clear of waste matter, which might lodge therein, during the depositing of the mineral. The baffle plates 19 as carried by the tubular members 16, provide means whereby the minerals as contained therein will be prevented from passing into the conveyer 1, yet allowing the lighter particles or waste to be readily passed thereby and delivered into the conveyer, whereupon the same is instantaneously gathered up by the motive fluid and passed through the discharge end of the separator.

It should be noted that the baffle plates 19 are formed above the pipe 20 and slant toward the ends of the pipe 20 entering the tubular members, thus causing an eddy of air under the baffle plates for removing the refuse particles from the tubular member. Also, the short pipes 20' connecting the tubular members of the pipes of the zig-zag

section 5 extend at right-angles to each other.

In operation, the free end of the straightaway portion 4 is connected with a suitable source of compressed air, while the free end of the uppermost portion 5 is connected with a discharge conduit 22, thus when the ore is fed into the conveyer by means of the hopper 9; the same will be carried forwardly through the various sections of the said conveyer, and the mineral products as contained being of greater weight, will be gradually deposited within the various pockets as constituted by the tubular members 16, the heavier particles of the minerals being deposited within the first series of pockets, while the remaining or lighter products are gradually delivered into the remaining pockets. Such waste material as may accumulate within the pockets will be promptly ejected therefrom by means of the shunt pipe 20, which pipe will deliver a blast of air into the said pockets, the force of which is sufficient to dislodge the lighter matter.

Other modes of applying the principle of my invention may be employed instead of the one explained, change being made as regards the construction herein disclosed, provided the means stated by any of the following claims or the equivalent of such states means be employed.

I therefore claim as my invention:—

1. In an ore separating device, the combination of a main piping, a plurality of sectional short pipings positioned in the same plane as the main piping, said short piping being substantially parallel, U-shaped elbows connected to the ends of said short piping, tubular members carried upon said short piping, short pipes connected to said tubular members, said short pipes extending at right-angles to each other, thus causing abrupt abutments for the particles of ore being drawn through said piping and pipes by air, so as to cause the minerals to be readily deposited in said tubular members.

2. In an ore separator, the combination of a piping having a material delivery means, an air forcing means communicating with said main piping, said piping having tubular members formed thereon and depending therebelow, a short pipe connected to said tubular members, one end of said last mentioned pipe projecting into said first mentioned pipe, baffle plates formed within said tubular members at points adjacent said first mentioned pipe, said baffle members extending downwardly into said tubular members, thus causing particles of refuse to be blown from said tubular members into said first mentioned pipe while allowing deposit of minerals to be retained in said tubular members.

3. In an ore separator, the combination of

a main piping, tubular members extending below said main piping having a material delivery means, an air forcing means communicating with said main piping, caps 5 detachably carried upon the lower ends of said tubular members, an auxiliary piping communicating with the interiors of said tubular members and being connected to said main pipe, thus causing air to be forced 10 through said auxiliary pipe from said main pipe, baffle plates formed in said tubular members adjacent the upper ends thereof, said baffle plates being formed upon the tubular members at sides opposite to the ends

of said auxiliary pipe thereinto, said baffle 15 plates extending downwardly toward the entrance ends of the auxiliary pipe, thus causing the air injected into said tubular members to be agitated below said baffle plates for quickly and thoroughly removing 20 refuse particles from said tubular members and directing the same into said main pipe.

In testimony whereof I affix my signature in presence of two witnesses.

RODERICK W. HADDOCK.
